(57) **CLAIM**

We claim the ornamental design for a flush mounted game controller holster, as shown and described.

DESCRIPTION

FIG. 1 is a perspective view of a flush mounted game controller holster showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a front cross-sectional view taken along the line 8-8 in FIG. 2;

FIG. 9 is a right cross-sectional view taken along the line 9-9 in FIG. 2; and,

FIG. 10 is an exploded view of the flush mounted game controller holster of FIG. 1.
